UNITED STATES PATENT OFFICE.

LOUIS N. JACOBI, OF CHICAGO, ILLINOIS.

RESILIENT HEEL.

1,019,898.

Specification of Letters Patent. Patented Mar. 12, 1912.

Application filed February 24, 1911. Serial No. 610,510.

To all whom it may concern:

Be it known that I, LOUIS N. JACOBI, a citizen of the United States, and a resident of the city of Chicago, county of Cook, and 5 State of Illinois, have invented certain new and useful Improvements in Resilient Heels, of which the following is a specification.

My invention relates to improvements in resilient heels for boots and shoes and has 10 for its object the production of a heel of this character which will be so constructed that the incorporation thereof in a shoe will render the latter more comfortable and better adapted for use in walking.

15 A further object is the production of a heel as mentioned which will be of durable and economical construction, one which may be readily and quickly applied to a shoe and one which will be of great efficiency in use.

20 Other objects will appear hereinafter.

With these objects in view my invention consists in a resilient heel characterized as above mentioned and in certain details of construction and arrangement of parts all 25 as will be hereinafter more fully described and particularly pointed out in the appended claim.

My invention will be best understood by reference to the accompanying drawings 30 forming a part of this specification, and in which,

Figure 1 is a sectional side elevation of a shoe to which is applied a heel embodying my invention, Fig. 2 is an enlarged bottom 35 plan view thereof, Fig. 3 is an enlarged section taken on substantially line $x-x$ of Fig. 1, Fig. 4 is an enlarged perspective of the resilient section of the heel, and Fig. 5 is a perspective detail of the spring-carrying 40 plate included in the invention.

The preferred form of my construction as illustrated in the drawings comprises a heel consisting of a central or intermediate resilient section 1 which is formed preferably of rubber, said section being of the usual peripheral form. Arranged upon the upper and lower sides of said section 1 are rigid sections 2 and 3 respectively, said sections being of less thickness than the section 45 1 and formed preferably of leather. The sections 1, 2 and 3 are secured together adjacent their peripheries by stitching 4 which extends entirely through the same, as clearly shown in Fig. 1, the construction being such, 50 as will be observed, that although said sections are securely fastened together the free-

dom of the intermediate section 1 for compression is not impaired, the stitching or sewing being flexible to permit of such.

Provided centrally in the intermediate 60 section 1 is an opening 5 extending completely through the same, thereby forming an interior chamber in the heel which is closed at its upper and lower sides by the sections 2 and 3 respectively. Arranged in 65 this chamber, that is in the opening 5, at the bottom thereof is a metallic plate 6 which rests directly upon the upper side of the section 3. Said plate is of a peripheral form identical with that of the opening 5 70 and of dimensions such that when arranged in said opening, said plate will be securely held therein its engagement with the sides of the opening preventing any relative movement. Arranged upon the upper side 75 of said plate is a compression spring 7 preferably of the coiled type and conical, the upper end of said spring resting forcibly against the under side of the section 2. Provided upon opposite sides of the plate 6 are 80 ears 8 which are bent into engagement with the lowermost or base convolution of said spring, said ears serving, as will be observed, to securely hold said spring in position upon said plate, thus preventing relative movement thereof in the heel.

In use, the heel above described is secured to a shoe by means of nails or pegs 9 which extend through only the section 2 of said heel into engagement with the rearmost or 90 heel portion of the sole 10 of the shoe, the latter being designated as 11. In order to permit of such attachment of the heel, that is of the attachment thereof through the medium of the nails 9 which pass only 95 through the section 2, the sections 1 and 3 are perforated as at 12 so as to permit of the passage of said nails into engagement with the section 2, as clearly shown in Fig. 1. Were the construction such that 100 the nails or pegs 9 projected and engaged all of the sections of the heel, that is 1, 2 and 3, said nails, because of their rigid nature, would impair the freedom for compression of the intermediate section 1 and 105 thus defeat the purpose of the heel. With the construction as set forth wherein the nails do not pass through the sections 1 and 3 but only the section 2 all interference with the free movement or action of the resilient section 1 will be obviated, the resulting heel 110 being absolutely free for compression and

thus adapted to absorb all shocks to which the heel is subjected in walking.

Upon the under side of the section 3 is preferably arranged a cover section 13 preferably of a durable tenacious leather, secured to the section 3 by means of nails or pegs 14, the latter, as will be observed, projecting only through said section 3. The section 13 closes the outer ends of the passages 12 and 10 is provided to receive all wear to which the heel is subjected when in use.

A heel of the construction as set forth is durable and economical, the provision of the resilient section 1 and the spring 7 resulting in a heel possessing to a high degree resiliency and durability and in the production of a heel well adapted to absorb shocks so as to conduce to ease and comfort in walking. The heel because of its simplicity in construction may be manufactured at a low cost and is adapted to be readily and quickly attached to a shoe for use.

While I have illustrated and described the preferred construction for carrying my invention into effect this is capable of variation or modification without departing from the spirit of the invention. I, therefore, do not wish to be limited to the precise details of construction as set forth but desire to avail

myself of such variations and modifications as come within the scope of the appended claim.

Having described my invention what I claim as new and desire to secure by Letters Patent is:

A resilient heel, comprising upper and lower leather sections; an intermediate rubber section, said sections being of similar peripheral forms and sewed together adjacent their peripheries, said intermediate section being provided with a medial oblong opening; a metallic plate of the same form and fitted into the bottom of said opening upon said rigid section, said plate being provided with upwardly extending ears at its edges, and a coiled compression spring fastened upon said plate by means of said ears and having its upper end resting in engagement with the underside of said upper section, substantially as described.

In testimony whereof I have signed my name to this specification in the presence of two subscribing witnesses.

LOUIS N. JACOBI.
